UNITED STATES PATENT OFFICE

ROBERT W. BRIGGS AND FLOYD COLE, OF PHARR, TEXAS

WIRE CUTTING AND TWISTING DEVICE

Application filed January 28, 1933. Serial No. 654,039.

This invention relates to wire cutting and twisting machines or devices.

An object of this invention is to provide a manually operable wire cutter and twisting means which is so constructed as to clamp the strands of wire within the device at the same time the strands are cut so as to permit the twisting of the device and strands of wire together.

Another object of this invention is to provide a device of this kind which is so constructed that it can be used substantially as a crank or turning means to rotate the device about the wire strands while holding the ends of the strands together and thereby twisting the strands one about the other.

The above and various other objects and advantages of this invention will in part be described and in part be understood from the following detailed description of the present preferred embodiment, the same being illustrated in the accompanying drawing wherein:

Figure 1 is a longitudinal section partly in detail of a device constructed according to the preferred embodiment of this invention.

Figure 2 is a fragmentary front elevation of the device.

Referring to the drawing wherein like numerals of reference designate corresponding parts throughout the several views, the numeral 10 designates generally a tubular handle of desired length, which has secured thereto a block 11 as by a pin or screw 13, and this block 11 has a pair of arms 12 integral therewith extending outwardly of one end of the handle 10 and extending at substantially a right angle to the longitudinal axis of the handle 10 and laterally thereof.

A curved tubular member 14 having a bushing or sleeve 15 secured thereto is rotatably mounted within the handle 10 and is held against longitudinal movement in at least one direction by means of a cap 16, which is threaded onto the opposite end of the handle 10.

Ball bearings or anti-friction elements 17 are interposed between the cap 16 and the outer end of the bushing 15, so that the

handle 10 may be rotated relative to the curved tubular member 14. A substantially U-shaped fixed jaw 18 is formed with the tubular body member 14, and this jaw 18 has an opening 19 to receive strands of wire. The jaw 18 has a cutter 20 on one side of the opening 19, and a movable or rocking jaw 21 is mounted on a pivot 22 carried by the fixed jaw or head 18 and is swingable across the opening 19, and is adapted to coact with the fixed cutter 20 in shearing or cutting the strands of wire positioned in the jaw opening 19.

A movable jaw operating means, generally designated as 23, is connected at one end as by a connector 24 to the movable jaw 21, and this jaw operating means 23 includes a plurality of spherical members 25 in the form of balls, which are mounted within the tubular member 14.

A plunger 26 is slidably mounted at one end in the inner end of the tubular member 14 and abuts against the innermost of the spherical members 25. The opposite end of the plunger extends through the bearing block 11, and is provided with a head 27 abutting against the curved portion 28 of a pivoted lever 29 carried by the arms 12.

An expanding spring 30 engages at one end against a seat 31 formed in the bearing block 11, and the opposite end of the spring 30 engages against the head 27 so as to constantly maintain this head 27 in contact with the curved portion 28 of the lever 29. A lug 32 is carried by the lever 29 at the pivoted end thereof, and is adapted to engage against a stop pin 33, which limits the rocking of the lever 29 in open or inoperative position.

The movable jaw 21 confronts a clamping jaw 34 mounted on a pivot 35. The clamping jaw 34 has the inner or free end thereof disposed in contacting relation with a cut-out portion 36 in the lower or movable clamping jaw 21. A spring 37 engages at one end against the clamping jaw 34 and at the opposite end against a flange 38 formed with the fixed jaw member 18. A threaded stop 39 extends through the spring 37 and has one end thereof disposed adjacent the

jaw member 34 and limits the rocking movement of this jaw member 34 under the pressure applied by the movable jaw 21.

5 A spring 40 is secured at one end to the free end of the movable jaw 21 and at the opposite end, as at 41, to the tubular body member 14. This spring 40 acts to constantly urge the movable jaw 21 into open position and to maintain the member 24 into 10 contact with the balls 25 so that these balls 25 will be held into contacting relation with each other at all times.

15 In the use and operation of this device, the wire strands are passed through the jaw opening 19 with the movable jaw 21 in released position. The lever 29 is then rocked toward the handle 10, which action forces the plunger 26 inwardly of the handle and moves the jaw 21 into shearing position relative to the cutter 20 so that the strands of wire positioned within the opening 19 will be cut by the movable cutting jaw 21, which operates as a shears to cut off the strands of wire. At the same time the movable jaw 25 20 coats with the fixed jaw 20 to shear the wire, the severed strands of wire will be clamped between the jaws 21 and 34. These strands will be held in parallel relation to each other and with the wire strands as a 25 pivot, the handle 10 including the lever 29 is swung in a circular movement about the wire strands, thereby twisting these strands together and tightening the wire upon a package, box or the like. Due to the rotatable mounting of the handle 10, the device can be readily rotated with the curved extension 14 acting as a lever to twist the wire strands together which are clamped between the two jaws 21 and 34.

40 It will be apparent from the foregoing that one of the strands of wire may be positioned with the end thereof substantially abutting against the inner face of the cutter 20 while the other strand which may be connected to a roll or spool of wire may be passed entirely through the jaw opening 19. The extension 14 constitutes a fixed part of the handle and acts to offset the handle 10 from the fixed jaw so that the desired pressure or leverage can be applied to the twisting of the wire.

45 It will be apparent, therefore, that there will be no loss of wire due to the cutting of the wire either before or after it has been 50 twisted upon the package, and that the original tension applied to the wire in the wrapping thereof can be increased by the tension applied under the twisting action as the handle 10 is swung or moved in a circular path about the wire strands.

55 It is, of course, understood that various changes and modifications may be made in the details of construction and design of the above specifically described embodiment of 60 this invention without departing from the

spirit thereof, such changes and modifications being restricted only by the scope of the following claims.

What is claimed is:

1. A wire cutting and twisting means 70 comprising in combination, a pair of cutting members, a substantially L-shaped handle secured to the members, said handle having one portion thereof movable relative to the other, and clamping means for clamping a wire in a manner to permit twisting of a plurality of strands of wire one about another upon turning of the handle in a circular motion about the clamping means.

75 2. A wire cutting and twisting means comprising in combination, a pair of cutting members, one of said members being fixed and the other movable, a substantially L-shaped handle carried by said fixed cutting member, said cutting members being disposed adjacent the end of one leg of said L-shaped handle, operating means carried by the other leg of the handle and engaging the movable blade to move said blade into cutting position, and means for clamping a stranded wire adjacent said cutting members in a manner to permit turning of one leg of the handle in a circular movement about the stranded wire with the wire as a pivot.

80 3. A wire cutting and twisting means 90 comprising a pair of cutting members, one movable relative to the other, a substantially L-shaped handle secured to one of the cutting members, said handle including a rotatable portion on one leg, a clamping means 95 carried by the handle and coacting with the cutting members to securely hold a stranded wire therebetween upon severance of the wire by the cutting members, and means carried by the handle and engaging one of the cutting members to move said cutting member into operative position.

100 4. A wire cutting and twisting means 105 comprising the combination of a pair of cutting members, a handle fixedly secured to one of the cutting members, said handle including a substantially L-shaped member having said one cutting member adjacent the end of one leg, the opposite leg including a rotatable portion, a lever carried by the handle and engaging about said rotatable portion thereof, and means extending through both legs of the handle and engaging the other of the cutting members and engaging the handle to rock said cutting member coactive with the rocking of the lever.

110 5. A wire cutting and twisting means 115 comprising a substantially L-shaped handle having a rotatable portion on one leg, a pair of cutting members secured to the other leg, a longitudinally movable operating member extending through the handle and engaging the other of the cutting members, a lever carried by the handle and engaging the operating member to move said operating 120 member.

member into operating position, yieldable means engaging the operating member to constantly urge said operating member into inoperative position, and means carried by the handle and one of the cutting members to securely clamp an article therebetween which has been cut off by the cutting member.

6. A wire cutting and twisting means comprising in combination, a pair of wire cutters, a handle for said cutters of substantially L-shaped construction, said handle having a rotatable gripping means on one leg thereof, and a clamping means carried by the cutters and coacting therewith to clamp an article therebetween which has been cut off by the cutters.

7. A wire cutting and twisting means comprising in combination, a pair of cut-

ting members, a handle carried by one of the members and positioned in offset relation thereto, clamping means carried by the cutting members to hold an article therebetween which has been cut off by the cutting members, and clamp operating means carried by the offset portion of the handle.

8. A wire cutting and twisting means comprising in combination, a pair of cutting members, a clamping means carried by the cutting members, a swivelled handle structure carried by one of the members with a portion thereof offset from the clamping means, and operating means for said cutting members and said clamping means carried by the offset portion of the handle.
